SOLO ELECTRICAL MUSICAL INSTRUMENT

Nicholas Langer, New York, N. Y., assignor to
 Central Commercial Company, Chicago, Ill., a
 corporation of Illinois

Application October 24, 1942, Serial No. 463,291

9 Claims. (Cl. 315—228)

1

The present invention relates to electrical musical instruments, and, more particularly, to an electrical musical instrument of the monophonic, or melody, type.

It is an object of the present invention to provide an electrical musical instrument of the described type having a novel and improved character and presenting substantial advantages over conventional electrical musical instruments.

It is another object of the present invention to provide an electrical musical instrument of the melody type, capable of producing a single musical sound at a time within a relatively wide range of pitch and tonal quality.

It is a further object of the present invention to provide an improved electrical musical instrument of the solo, or melody, type in which a single oscillator tube of the gaseous discharge type is adapted to produce musical oscillations over a musically useful range of several octaves and having a large variety of tone colors or timbres, without recurring to the heretofore employed complex procedure of employing a plurality of octavely related cascaded oscillators.

Still another object of the invention is to provide a monophonic electrical musical instrument employing a single glow-discharge tube oscillator operatively associated with a keyboard or playing manual of relatively restricted range and adapted to control the pitch of the oscillations produced within a considerably greater musical range.

Still another object of the present invention is to provide an electrical musical instrument originally producing electrical oscillations of very complex waveform which may be readily converted into musically useful and valuable oscillations of a great variety of tone colors, simulating the tone colors of most of the orchestral instruments and in addition to this also capable of producing many additional tone colors of an altogether novel character not now found in conventional musical instruments, or in the stops of conventional organs.

Moreover, the invention provides means and instrumentalities for producing additional tonal effects, particularly tremolo effects and percussion type effects resembling those of plucked strings by inertialess or electronic means in the absence of mechanical interrupters, and similar conventional devices.

2

The invention also provides novel tone color modifying circuits and devices capable of being adjusted to a practically unlimited number of distinctly different tone colors without requiring any complex electronic devices for the purpose of phase shifting, distortion and the like effects now commonly used for such purpose.

It is also within the contemplation of the invention to provide an electrical musical instrument including a glow-discharge oscillator of special type which is free from the detrimental effects of leakage and atmospheric variables and is capable to maintain its correct tuning for a relatively long time.

15 The invention also contemplates an electrical musical instrument of the melody type, which is extremely simple in construction and generally includes only a single oscillator tube, provides excellent musical effects of a practically unlimited variety, and which may be readily manufactured and sold on a practical and commercial scale at a low cost.

Other and further objects and advantages of the present invention will become apparent from 25 the following description taken in conjunction with the accompanying drawings, in which

Fig. 1 illustrates in a somewhat fragmentary manner the circuit diagram of an electrical musical instrument embodying the principles of 30 the present invention.

Fig. 2 depicts the circuit of a preferred form of tone filter system employed in connection with the electrical musical instrument illustrated in Fig. 1; and

35 Fig. 3 shows the circuit diagram of a universal tone filter system which in combination with an oscillation generator producing oscillations of complex wave form is capable of producing a practically endless variety of different tone colors.

40 The invention will be best understood from description of a preferred embodiment thereof reference being had to Fig. 1 of the drawings. In order to facilitate understanding of the invention such elements which are of a more or less conventional character and are well known to those skilled in the art, such as the source of current, or power pack, the amplifier and volume control, have been either omitted, or have been only diagrammatically shown.

45 Generally speaking, the electrical musical instrument of the invention comprises a main oscillator section, a range control section, a

tremolo-banjo section and a tone control or output section.

Main oscillator section

The main oscillator section essentially comprises an oscillator tube of the gaseous discharge type which is operatively associated with a source of direct current voltage and with a plurality of tuning elements, such as condensers and resistors of determined value to produce electrical oscillations the frequency of which may be varied in steps within a wide range.

Referring now more particularly to Fig. 1 of the drawings, reference character 10 denotes a source of direct current of suitable voltage which in practice is a power pack converting the alternating current taken from the electric mains into filtered direct current of substantially stable voltage. In most cases this power pack may be in common with that of the amplifier in view of the fact that the total current consumption of the instrument is relatively low. Between the positive and the negative terminals of this source of direct current is connected a voltage divider resistance 11 from which various operating voltages may be taken off for the different sections of the instrument, this resistance being connected in series through lead wire 12, and switch 13 to a group 14 of individual tuning potentiometers comprising a number of small potentiometers 15 connected in parallel, the other end of said group being connected to ground through lead wire 16. Voltage divider resistance 11 is provided with sliders 17 and 18 to take off voltages of desired value, as it will appear more fully hereinafter, and its total resistance is so adjusted that the voltage drop across each of the tuning potentiometers 15 is about 4 to 6 volts. Condensers 19, 20, 21 and 22 are connected across the various taps of voltage divider resistance 11 and ground in order to reduce the alternating current resistance of the system to a relatively low value.

Between the two taps 17 and 18 of voltage divider 11 is connected main pitch control potentiometer 23 which serves to adjust the operating voltage of the oscillator tube and thereby controls the general pitch of the instrument. With the movable arm of this potentiometer are connected in series tremolo coupling resistor 24, pitch balancing resistor 25 and output resistor 26, together with glow-discharge tube 27, range control switch 28, tuning condenser 29, the latter being connected to the negative terminal of the source of current 10. While any glow-discharge tube of good make and of stable characteristics may be used, I found that a glow-discharge tube of type VR75/30 provides excellent results.

To the common terminal of tube 27 and condenser 29 is connected a chain of fixed resistors which comprises serially connected resistances 30, 31, 32, 33, 34 . . . 34n. These resistances correspond in number to the number of notes of different pitch which may be produced in a single range of instrument. Thus, for example, for an instrument having a range of three octaves from C to C, 37 resistances are used and their resistance is so determined that upon connecting a selected serially connected plurality thereof across tuning condenser 29, the oscillator will be approximately tuned to notes of successively decreasing pitch in correspondence with successive notes of the tempered scale. Between the common terminal of any two adjoining resistances there is connected a switching key 35, 36, 37, 38,

39 . . . 39n, one contact of which is connected through a balancing resistance 40 to the sliding contact of one of the potentiometers 15 of group 14 and then through common lead 16 of such group to ground. Thus, it will be noted that upon closing of any one of key switches 35 to 39, etc., a predetermined number of the serially connected resistances 30 to 34n will be connected across condenser 29 through one of balancing resistances 40 and through one of potentiometers 15. Selection of the proper value for resistances 31 to 34n permits approximate tuning of the respective note, while displacement of the slider on the corresponding potentiometer 15 will permit to individually adjust the operating voltage effective upon depression of said key and thereby to accurately adjust the pitch for that note. In this connection it may be pointed out at this time that the value of resistances 31 to 34n, balancing resistances 40 and individual tuning potentiometers 15 are of a different order. For example, when main tuning resistor 30 is of about 1,500,000 ohms, resistance 31 to 34n may be of progressively increasing values from about 70,000 to about 500,000 ohms, balancing resistors 40 may have a resistance of about 25,000 ohms each and individual tuning potentiometers 15 may have a resistance of 5,000 ohms each. The object of such coordination of resistance values will appear as the description proceeds.

Range control section

Generally speaking, it is not advisable to provide a single range greater than about 3 octaves for various practical reasons. First of all, the extension of a single range obviously determines the number of switches and thereby the length of the playing manual. In addition, as the total resistance of the resistance chain 31 to 34n increases with increasing range, if the range is unnecessarily extended, the relation between the value of resistances in the circuit and the permissible leakage becomes unfavorable and affects the permanency or stability of tuning. A range of 3 octaves is in most cases sufficient for playing any melody with the accompaniment of another instrument, such as a piano. In order to permit operation within various ranges of tone frequencies, such as soprano, alto, tenor or bass ranges, it is preferred to shift the range of the oscillator as a whole by one or more octaves. In the circuit of Fig. 1 two such ranges are shown, it being understood that, of course, three or more different ranges may be incorporated into the instrument, if desired.

Range shifting is accomplished by means of range shifting switches 13 and 28 which are preferably combined into a single unit of the double-pole, double throw type, so that these two switching operations are simultaneously performed. Of these switches, 28 switches tube 27 over into series connection with condenser 41 from condenser 29. The relationship between the capacities of 29 and 41 substantially determines the frequency difference between the two ranges. Thus, for example, if condenser 41 has a capacity twice as great as that of 29, the pitch of the instrument will be lowered by an octave, if condenser 41 has a capacity four times as great as that of 29, the pitch of the instrument will be lowered by two octaves. While the range-changing effect of the capacity in the oscillator circuit is more or less equal for all of the frequencies corresponding to actuation of the various key

switches, certain slight differences frequently occur due to the different impedance of the other portions of the circuit at widely different frequency ranges. Therefore, to obtain and to maintain musically perfect and correct pitch for the several ranges, it is desirable to also provide a second group 42 of individual tuning potentiometers 43 for the second range. It will be readily observed that in the first or "high range" position of the instrument, this second group of 10 tuning potentiometers is not energized, one of its bus bars being disconnected at switch 13. In the second or "low range," however, group 42 will be energized and group 14 will be disconnected from the voltage divider resistance 11. In this case depression of any one of switching keys will connect a controlling potential to the oscillator tube determined by the setting of the corresponding potentiometer of group 42. This potential is delivered to the tube through the resistance chain 30 to 34n and through a balancing resistance 44 which corresponds in function and in value to the balancing resistors 40 connected between the keying switches and the sliding contacts of potentiometer group 14.

The object of the provision of the balancing resistors 40 and 44, one set for each group of tuning potentiometers, is to substantially eliminate the effect of the setting of the unenergized group of potentiometers upon the energized group of potentiometers. As it will readily appear from Fig. 1, each switching key is at all times connected to the sliding contact of two potentiometers, one in each group, through a balancing resistance. Assuming that, for example, group 14 of the potentiometers is energized, a predetermined potential, generally different from ground potential is applied to the switching key in accordance with the setting of the respective potentiometer. At the same time, however, a portion of this potentiometer is shunted by a secondary current path comprising the two balancing resistors 40 and 44 in series, lower bus bar 45 of group 14 and lower bus bar 46 of group 42, the slider of a potentiometer 43 in group 42 and a portion of said potentiometer. Due to the fact however, that the balancing resistances have a considerably higher resistance than the potentiometers, the effect of this by-passing resistance on the setting of the energized potentiometer will be negligible. Thus, for example, if the individual potentiometers have a resistance of 5,000 ohms each and the balancing resistances have a resistance of 25,000 ohms each, the by-passing resistance will be in excess of 50,000 ohms, while the portion of the potentiometer across which such resistance is connected is generally considerably less than 5,000 ohms so that the setting of the energized potentiometer 15 will be the governing factor whereas the setting of the other potentiometer in the second group will be of practically no effect. This arrangement is of considerable importance and value because otherwise it would be necessary to provide a complicated and bulky multiple switch arrangement capable of switching over as many as 37 key contacts from one group of potentiometers to the other. It is also worth noting that the total resistance of the current path between the lower terminal of any one switching key to ground through the respective balancing resistor and tuning potentiometer is quite low with respect to the resistance of the resistance chain 30 to 34n at that point. Generally speaking, the former resistance is only slightly in excess of about 25,000 ohms whereas the resistance chain

may have a resistance of 1.5 million ohms up to 10 million ohms, and more, according to the keying switch actuated. This proportion of the resistances is of considerable importance in assuring that upon actuation of several switching keys at the same time always the higher note will sound, as it will be explained more fully when the operation of the instrument will be described.

Tremolo and banjo sections

The main oscillator section and the range shifting section in proper cooperation are capable of producing a single sustained note of complex wave form over a range of several octaves, such as, for example, three octaves, this range being shiftable by 1 or 2 octaves up or down by actuating the range-shifting means described in the foregoing. It has been found desirable to incorporate means for producing a tremolo, that is: to cause slight periodic changes in the pitch of the oscillations produced, such periodic changes having a relatively slow rate such as about 6 or 7 times a second. Such periodic changes in pitch provide a musically valuable result similar to the well-known vibrato effect of the string instruments and of the singing voice.

In accordance with the principles of the present invention, the tremolo effect is obtained by means of an auxiliary glow-discharge tube oscillator tuned to a very low frequency, such as 6 or 7 oscillations per second. This tremolo oscillator is so coupled with the main oscillator circuit that every time when the tremolo oscillator draws current from the common source, the available operating voltage for the main oscillator is somewhat decreased. Decreasing operating voltage causes decreasing frequency of the main oscillator.

In Fig. 1, reference character 47 denotes the tremolo tube, which preferably is a glow-discharge tube having two cold electrodes. One terminal of this tube is connected to the common point of pitch-balancing resistor 25 and output resistor 26, the other terminal of the tube being connected through a fixed resistance 48 of about 1,500,000 ohms and an adjustable resistance 49 of about 2,000,000 ohms to ground. Two condensers 50 and 51 of about 0.15 and 0.1 microfarad capacity, respectively, have one of their terminals connected to the common terminal of tube 47 and resistance 48, their other terminals being respectively connected to two arms 52, 53 of a three-pole three-position switch 55. The third arm, 54, of switch 55 is connected across pitch-balancing resistor 25 and is capable of shorting the same in the third position of the switch through lead wires 56 and 57. It will be noted that in the first position of the switch, as illustrated in Fig. 1, arm 52 of the switch will connect condenser 50 across tube 47 while the other two arms of the switch are inoperative. In this position slow oscillations will be produced by tube 47 and the tube will be lighted and extinguished about 6 or 7 times per second. Every time the tube is lighted, in addition to the current flowing to the main oscillator, additional current will be drawn through resistors 24 and 25, and the voltage drop across these resistors will slightly decrease the frequency of the main oscillator at the same rate as the tremolo oscillator is oscillating. The speed of the tremolo is determined by the value of elements 50, 48 and 49, and may be approximately adjusted by proper selection of 50 and accurately adjusted by the adjustment of resistance 48.

When switch 55 is placed into its third position, arm 52 will be inoperative, arm 53 will connect condenser 51 across resistors 48 and 49 and arm 54 will short-circuit pitch-balancing resistor 25. Connection of condenser 51 across resistors 48 and 49 will likewise cause oscillations of tremolo tube 47, but the wave form will be greatly different. While the tube with a condenser across the same produces a wave form characterized by slow charge and rapid discharge of the condenser through the tube, connection of the condenser across the resistance will produce almost instantaneous charging of the condenser through the tube and gradual discharge of the condenser through the resistance across the same. The latter arrangement gives a wave form with very abrupt peaks which superimposed upon the main oscillator by means of tremolo or coupling resistor 24 causes such modulation of the main oscillation which closely simulates the sound of a string, plucked or struck in rapid succession. In the following, this effect, which is very attractive musically, is referred to as "banjo effect." In view of the fact that generally faster oscillations, about 10 to 12 per second are required for this banjo effect, condenser 51 has a lower capacity than condenser 50 to take care of the difference of speed between the tremolo and banjo effects.

Experience has shown that in general the tremolo oscillator has a slight effect upon the general pitch of the main oscillator. More particularly, switching over from tremolo to banjo would slightly raise the general pitch of the main oscillator. To compensate for this undesirable change, is the object of the provision of pitch-balancing resistor 25 which is in series with both the tremolo and the main oscillator tube. Shorting out of this resistor of about 15,000 ohms simultaneously with switching over from tremolo to banjo effect will lower the pitch of the main oscillator by the same amount as it would be raised by the different impedance of the auxiliary oscillator in the banjo connection. In this manner, the pitch will be maintained constant regardless of whether the tremolo or the banjo effect is used.

In the middle position of switch 55 all three arms thereof are inoperative. This is the neutral position in which the auxiliary oscillator does not produce any oscillations. It is worth noting that tube 47 is continuously lit in this case, its circuit being completed from the positive terminal of the source of current 10 through resistors 24 and 25 and then through resistors 48 and 49 to ground. This is essential in order to avoid any change in the general pitch of the main oscillator in the tremolo-off position.

Output and tone control section

The output signal is taken off at a resistance 26 connected in series with the main oscillator circuit. Any change in the impedance of the output circuit is likely to change the general pitch of the oscillator. Therefore, to substantially eliminate such changes, it is desirable to have the coupling between the oscillator proper and the output circuit as loose as possible. This is accomplished by making the value of output resistance 26 relatively small with respect to the internal resistance of the oscillator circuit such as, for example, 10,000 ohms. The signal corresponding to the voltage drop along resistance 26 is introduced into the primary winding 58 of an output transformer 59 through a decoupling resistance

68 having a value of about 25,000 ohms. One end of the secondary winding 61 of transformer 59 is connected to ground through shield 62 while the other through a lead 63 shielded by means of shield 62 is introduced into the tone control device generally denoted by reference character 64. A second decoupling resistance 65 of about 25,000 ohms is preferably connected in series with this lead to prevent changes in the output impedance being reflected back into the main oscillator circuit and thereby causing slight pitch variations.

The tone control device has the object of converting the oscillations originally produced by the oscillator and generally having an extremely complex saw-tooth wave shape into other oscillations of different wave form by filtering out some of the harmonics and by reinforcing others. The tone control device essentially comprises a plurality of switches such as for example eight switches of the push button type which can be actuated individually or in any desired combination of two or more switches at a time. By actuating these switches, filter systems 1 to 8 may be selectively connected in series with the outgoing signal, passing through some of the oscillations in modified form and grounding other portions of harmonics of the oscillations through a lead wire 66.

While the general principles governing the frequency response of various filter circuits comprising capacitors, inductances and resistors in various combinations are known, the theoretical determination of filter systems to obtain a certain musical result is so involved and uncertain in the final result that experiment has been found the simplest and quickest way to decide the type and the value of the electrical elements for obtaining a wave form simulating a determined musical tone color.

I have found that excellent results are obtained by means of small transformers employed as inductances in filter circuits with or without combination with other elements such as condensers and resistances. Transformers of the type used in amplifiers as interstage coupling transformers are especially advantageous because they are readily obtainable on the market with a great variety of winding ratios and taps and also because they are relatively small and inexpensive. A single transformer may be used to selectively provide a plurality of widely different inductances according to whether the primary winding, the secondary winding, or only a portion thereof is used. I have also found that by unipolarly introducing the signal into one of the windings of the transformers and unipolarly withdrawing the signal from the other winding also provides novel and interesting filtering effects. A transformer used in such a manner corresponds to an electrical filter of unique characteristics in that the signal is transferred from one winding into the other by means of a combination of uniformly distributed capacitive and inductive coupling, which deforms the original wave pattern in a manner unobtainable in any other way. It is also possible to employ one winding of a transformer as an inductance and to short circuit the other winding either directly or through a highly resistance or small capacity whereby further modified tone colors are obtained.

The electrical circuits incorporated into the tone color section will be best understood from Fig. 2 of the drawings. Reference character 75 generally denotes a filter system which is capable

of producing three distinctly different tone colors according to whether push button 1, 2 or 5 is actuated. The filter system comprises a small transformer 84 of the type used as interstage coupling in amplifiers having a secondary winding 85 with a greater number of turns than the primary winding 86. One end of winding 85 is connected to the upper terminal of a condenser 87 of about 0.003 mf., of which the lower terminal is grounded, and to one contact of both switches 78 and 68. The other end of said winding of transformer 82 is connected to contact 88 of double-throw single-pole switch 89. The center point 90 of this switch is connected to the upper terminal of another condenser 91 of about 0.003 mf., likewise grounded at the other terminal, and is also connected to one contact of both switches 69 and 67. The second stationary contact 92 of switch 89 is connected to the center tap of winding 85 of transformer 84 and also to one contact of switch 76 coordinated to push button unit 5 of which the other switch 75, has one of its contacts connected to one end of the other winding of the transformer.

This single filter combination is capable of producing three different tone colors. Thus, upon actuating push button 1, switch 67 and switch 68 are closed and switch 69 connects contacts 88 and 90. In this case the full winding 85 is connected between input bus bar 93 and output bus bar 94 and two condensers 87 and 91 are connected to ground at either end of such inductance. The result will be a tone color corresponding to flute in the high-pitch range of the instrument and to French horn in the low-pitch range of the instrument. Upon actuation of push button 2, both switches 69 and 70 are closed and only one half of the inductance will be connected between bus bars 93 and 94, the same condensers being connected between the ends thereof and ground. This produces a tone color corresponding to that of a soprano saxophone in the high-pitch range and to a bass clarinet in the low range. Upon actuation of push button 5, switches 75 and 76 are simultaneously closed and the signal will be introduced at the center tap of winding 85 of transformer 84 and is withdrawn through lead 93 connected to one end of winding 86 of the transformer. It will be noted that one end of winding 85 is floating, while the other end thereof is grounded through condenser 87, and that the other end of winding 86 is likewise floating. This filter of rather unusual construction produces a muted trumpet quality in the high range and an effect closely similar to vox humana in the low range.

Depression of push button 3 simultaneously closes switches 71 and 72, and connects a resistance 85 of about 50,000 ohms between bus bars 93 and 94, each end of said resistance being grounded through a condenser 96 and 97 of about 0.003 mf. This filter produces an excellent string quality corresponding to the tone color of a violin in the high range and to that of a 'cello in the low range.

Depression of push button 4 simultaneously closes both switches 73 and 74 and thus connects one half of winding 88 of a small interstage audio transformer 88 between bus bars 93 and 94. The other end of said winding is floating and so is the other winding 100, preferably the one with the lower number of turns. At the input end of winding 88 it is grounded through an inductance 101 of relatively high value and also of a relatively high direct current resistance such as, for ex-

ample, a small telephone coil of about 2000 ohms resistance, with its usual iron core. At its output end, winding 98 is grounded through a capacity 102 of about 0.004 mf. This stop provides an excellent oboe in the high range and a bassoon in the low range.

Push button 5 has been already discussed in the foregoing. Push button 6 upon actuation will simultaneously close switches 77 and 78 and thereby connects one winding of a small transformer 103 between the input and output signal bus bars 93 and 94. This transformer is of very small dimensions, such as are sometimes used in hearing aids and has a primary to secondary ratio of about 1 to 10, and a direct current resistance of about 45 ohms and 450 ohms, respectively. At the input end of the secondary or high resistance winding 104 there is a condenser 105 of about 0.003 mf. and an inductance 106 connected to ground. The inductance is a conventional telephone coil having a direct current resistance of about 4000 ohms. The other winding of the transformer 103 is either left floating or may be shorted by means of a high resistance 108 of the order of about 50,000 ohms. This shorting lead of predetermined resistance introduces distortion into the filter system, the amount of which can be accurately adjusted by the value of the resistance whereby a very precise control upon the resulting tone color is obtained. This filter gives a tone color or stop known in the organ art as musette in the high range and that of a sax horn in the low range.

Upon depression of stop button 7 switches 79 and 80 are simultaneously closed and a small transformer 109 having a primary winding 110 and a secondary winding 111 is connected in such a manner that the input bus bar 93 is connected unipolarly to one end of the primary and the output bus bar 94 is likewise unipolarly connected to the secondary winding at one end thereof. The transformer is of the same type as the one used in filter 6. As it has been already explained in the foregoing, a filter of this type has rather peculiar electrical characteristics in that it corresponds to a uniformly distributed inductance and a uniformly distributed capacity combined in a single electrical element. The resulting tone color is a trumpet in the high range and a tenor saxophone in the low range.

Stop button 8 simultaneously closes switches 81 and 82 whereby a direct lead 112 is connected between the input and output signal bus bars, said lead being by-passed to ground through an inductance 113. This inductance is a small telephone coil having 2000 ohms direct current resistance. The resulting tone color is corresponding to an organ stop commonly called flageolet, both in the high and low ranges.

The foregoing tone effects may be either individually employed by actuating a single push button, or stop, or two or even more stop push buttons may be simultaneously closed. In the latter case further interesting and pleasing tone colors are obtained rather than a direct additive effect of the individual stops. The following table should give some idea as to the principal tone colors obtainable by the judicious application of the foregoing stops. Whenever a number follows the name of a tone color or instrument, this indicates that while the resulting quality is similar to the instrument in question it is slightly different from another quality of the same name obtainable by means of another combination of stops. This can take care of in-

dividual difference of judgment or preference frequently found among different musicians.

Stop	High range	Low range
1.	Flute	French horn.
2.	Soprano saxophone.	Bass clarinet.
3.	Violin.	Cello.
4.	Oboe.	Bassoon.
5.	Muted trumpet.	Vox humana.
6.	Musette.	Sax horn.
7.	Trumpet.	Tenor saxophone.
8.	Flageolet.	Flageolet.
1 and 3.	Harmonic flute.	Do.
1 and 4.	English horn.	Do.
1 and 5.	Muted violin.	Muted cello.
1 and 6.	Gemshorn.	Do.
1 and 7.	Flauto traverso.	Viola.
2 and 4.	Oboe 2.	Bassoon 2.
2 and 6.	Quintadine.	Do.
3 and 4.	Oboe 3.	Bassoon 3.
3 and 5.	Viola 2.	Cello 2.
3 and 6.	Oboe 4.	Bassoon 4.
3 and 7.	Viola d'amour.	Do.
4 and 6.	String.	Do.
4 and 7.	Muted string.	Do.
5 and 6.	String.	Do.
5 and 7.	Woodwind.	Do.
6 and 8.	Shepherd's pipe.	Do.

After the output of the instrument has been appropriately modified by means of the tone color filters, the output taken off at output bus bar 34 is introduced into a volume control potentiometer 114 of any appropriate taper and from this it is introduced into an amplifier 115 of suitable output and finally into a sound producing means 116. In view of the fact that the amplifier may be of any suitable type and does not form part of the present invention, it has been merely diagrammatically indicated.

Resistance 117 connected directly across main oscillator tube 27 has a very high value, generally in excess of 500 megohms, and may be up to 2000 megohms. This resistance has been found extremely effective in eliminating the variable effect of leakage on the permanency of tuning. As it has been set forth in the foregoing, certain portions of the circuit are very sensitive to leakage in view of the fact that some of the current-carrying portions of the circuit themselves have a very high resistance, such as the resistance chain 38 to 34n which might have a value of up to 10 to 15 megohms. A certain amount of leakage through the wiring and particularly through the keyboard contacts is practically unavoidable, particularly in humid weather. This is substantially compensated for by voluntarily introducing a leakage path of constant value which is much lower than the accidental and variable leakage in the circuit. Experience has demonstrated that this simple expedient practically completely eliminates all difficulties heretofore experienced in the constancy of tuning under unfavorable atmospheric conditions.

Operation

From the foregoing description, the operation of the electrical musical instrument embodying the principles of the present invention will be readily understood by those skilled in the art. Tuning of the instrument is carried out at the factory by employing a conventional musical instrument of very constant tuning, such as a reed organ, for standard, or by means of the same method as is now generally employed by trained piano or organ tuners. First of all, the general or standard pitch of the instrument is

adjusted by means of main tuning potentiometer 23. Thereafter, range switches 13 and 28 are placed in the high range position and the tuning of the individual notes is correctly and accurately adjusted by means of the individual tuning potentiometers of group 14 and then the same procedure is repeated for the low range by placing range control switches 13 and 28 into the low range position and by adjusting the individual tuning potentiometers of group 42. If at any time there is some discrepancy between the exact octave relationship of the high and low ranges, this can be readily corrected by adjustment of range control condensers 29 or 41, which are preferably of the mica compression type to facilitate ready and continuous adjustment. It has been found that the instrument is very stable in tuning and as a rule does not require retuning for long intervals of time.

Attention is directed here to the advantages provided by means of the main tuning potentiometer 23 which permits continuously adjusting the general pitch of the instrument within the range of a few notes, simultaneously for both ranges and without affecting the relative pitch of the various individual notes which will retain their correct intervals determined by the equal temperament. Thus, by means of this single control element, the instrument can be readily and instantaneously tuned to any standard pitch such as the international or the concert pitch or to any other instrument of constant tuning, such as a piano or organ, whatever its general pitch is. Moreover, the same feature of my instrument makes it a transposing instrument so that a melody written in a difficult key or tonality, such as C# major, may be instantaneously transposed into another very simple key. Thus, for example, by shifting the general pitch half a note higher, the operator may play a melody in C major and it will sound in C# major. This is a very great advantage not only for the operator having but limited musical knowledge or skill but also for the highly trained musician.

In playing the instrument little experience is required due to the fact that the playing manual controlling switching keys 35 to 39n is closely similar to a conventional piano keyboard with which most people are familiar. In view of the fact that only one note is produced at a time, the simple technic of depressing a single key at a time is easily mastered. In case at any time accidentally or intentionally more than one key is depressed at the same time, the highest key will be the controlling one, while the others have practically no effect on the resulting note. This will be readily understood from the circuit shown in Fig. 1. Provided that switching key 38 is depressed, in the high range, resistances 30 and 31 will be connected across condenser 28 through a balancing resistance 40 and an individual tuning potentiometer 15. If now also switching key 38 will be simultaneously depressed, this will cause additional connection of resistances 32 and 34 but these, having a value of several hundred thousand ohms will be practically short circuited by the low resistance path through a balancing resistor 40, two potentiometers 15 and another balancing resistor 40. This path is hardly in excess of 50,000 ohms.

The same applies when any number of keys is depressed at the same time, always the highest note will sound and at no time will be non-harmonic notes foreign to the scale produced. This circumstance is of great importance as in normal

playing, particularly in legato passages, the simultaneous depression of two keys at least transiently can be hardly avoided. This problem was quite serious in the art and to avoid the production of non-harmonic notes upon transient depression of two keys at the same time some inventors were forced to include complex switching devices into the instrument which upon depression of more than one key at a time completely de-energize the system and prevent production of any sound at all. Of course, this procedure does not provide any solution of the problem because when a legato passage is played, there will be a short interval between passing from one note to the next in which nothing will be heard and thereby it is made impossible to obtain a good legato effect, which is one of the principal attractions of a sustained-note melody instrument. The present invention provides a complete solution for this problem.

The sustained note of the instrument may be modulated or embellished by means of a tremolo effect by placing effect switch 55 into its upper position, or may be caused to imitate a plucked string by utilizing a banjo effect by placing said switch into its lowermost position. In the center or neutral position of the effect switch the produced note is unmodulated. The various tone colors may be readily and selectively obtained by actuating one or more of stop buttons 1 to 8 individually or in combinations, as it has been set forth more fully in the foregoing.

In some cases, it has been found desirable to provide filtering means, capable of producing any desired tone color by means of suitable adjustment thereof. A device of this type may be used in addition to the fixed filters described in the foregoing so that when a tone color or timbre is desired which is not included among the fixed stops, such timbre may be readily obtained by means of a few simple adjustments. A universal tone filter which has been found to provide excellent results is diagrammatically illustrated in Fig. 3.

As it will be readily observed in Fig. 3, my novel universal tone filter comprises six, or more, tap switches 118 to 123. Each of these tap switches has six contact points 1 to 6. Three of the switches 118, 119 and 120 are connected in series and form the horizontal portion of the resultant filter, and the rest of the switches 121, 122, and 123 are connected across the elements of the horizontal portion and the common ground lead 124. Each tap switch is capable of connecting various electrical elements, such as inductances, capacities and resistances of appropriate value into the filter circuit. For example, the respective values of inductances may be 0.5 to 2 henries of the capacitors 0.001 to 0.006 mf. and of the resistances 10,000 to 50,000 ohms. In addition, one of the taps of each horizontal switch may have a tap connected to a shorting lead 125, while the first tap of the vertical switches may be open. As those skilled in the art will readily understand, a device of this type is capable of providing filter combinations of an almost infinite number, more than one hundred thousand for the described number of taps, in which filters inductances, resistances and capacities may be connected in all conceivable ways. In general, each combination produces a different tone color when connected into the output circuit of the instrument of the invention. The universal tone control device of the invention is not only useful as an addition to any electrical musical instru-

ment, but is also extremely helpful for experimentally determining the filter system necessary to obtain a certain definite tone color. Thousands of combinations can be tested within a few hours, and, as soon as a tone quality of attractive timbre is found, the particular filter may be readily built up in the form of a fixed stop, if desired. Of course, the number of taps on each switch may be increased over six in order to accommodate more electrical elements such as inductances, capacitors and resistances of different size. Any tone color once obtained may be reconstructed in a few seconds, if record is made of the tap numbers to which the respective switches have to be set, each setting being characterized by six figures. Thus, for example, the figure 222,533 characterizes a filter in which three inductances are connected in the horizontal or series portion of the filter, and a condenser is connected after each inductance to ground. Obviously, the usefulness of my novel universal tone filter device is not restricted to my electrical musical instrument but can be used with good results in any electrical musical instrument in which the oscillators initially produce oscillations of relatively complex wave form.

Although the present invention has been described in connection with certain preferred embodiments thereof, variations and modifications may be resorted to by those skilled in the art without departing from the principles of the present invention. I consider all of these variations and modifications to be within the true spirit and scope of the present invention, as disclosed in the foregoing description and defined by the appended claims.

I claim:

1. An electrical musical instrument employing an electro-acoustic transducer, said instrument comprising in combination a space discharge device, a tuned mesh for said space discharge device, and including variable resistances connected in parallel, switching means for connecting selected resistances of said mesh into oscillation-producing relation with said space discharge device, a conductive path connecting said transducer in the output of said device, range-shifting means for said device, and correction means individual for each range to eliminate the effect of variables incidental to the change of range.
2. An electrical musical instrument employing an electro-acoustic transducer, said instrument comprising in combination a space discharge device, a series of tuning elements for said device, manually operable elements for connecting selected portions of said series in oscillation-producing relation with said space discharge device thereby to selectively produce frequencies approximately corresponding to notes of the tempered scale, a conductive path connecting the aforementioned transducer in the output of said device, range-control means for rendering said series operative in a plurality of ranges, and individual tuning means for each of said ranges to accurately adjust the resulting frequencies.
3. A solo electrical musical instrument employing an electro-acoustic transducer, said instrument comprising in combination a glow-discharge tube, a conductive path connecting said transducer in the output of said glow-discharge tube, a tuned mesh for said tube and including variable resistances connected in parallel, switching means for selectively connecting resistances of said mesh to said tube to approximately tune the same to frequencies corresponding to notes

of the tempered scale with in a range, means for shifting said range, and a set of individual tuning elements for each range for accurately adjusting the frequencies produced.

4. A solo electrical musical instrument employing an electro-acoustic transducer comprising in combination a glow-discharge tube, a conductive path connecting said transducer in the output of said glow-discharge tube, a series of resistances and a plurality of valuable condensers for said tube, switching means for connecting selected portions of said series in oscillation-producing relation with said tube thereby to approximately tune the same to frequencies corresponding to notes of the tempered scale within a range, switching means in selective coaction with said condensers to shift the range of said notes by a fixed amount, a set of individual tuning elements for each range for accurately adjusting the frequencies, and means for rendering said sets selectively operable concurrently with the shifting of range.

5. A solo electrical musical instrument employing an electro-acoustic transducer, said instrument comprising in combination a glow-discharge tube, a conductive path connecting said transducer in the output of said glow-discharge tube, a condenser in series with said tube and a plurality of serially connected resistances, switching means for selectively connecting a selected portion of said plurality across said condenser and in oscillation-producing relation with said tube thereby to cause said tube to produce oscillations of different frequencies within a determined range, switching means for changing the capacity of said condenser and thereby to change said range by at least one octave, a set of individual tuning potentiometers for each range to accurately adjust the frequencies produced, and means for selectively energizing said sets of potentiometers in accordance with the range which is operative.

6. A solo electrical musical instrument employing an electro-acoustic transducer, said instrument comprising in combination a glow-discharge tube, a conductive path connecting said transducer in the output of said glow-discharge tube having capacitive means connected in series therewith, a series of resistances, switching means for selectively connecting a selected plurality of said series across said capacitive means and in oscillation-producing relation with said tube thereby to cause said tube to produce oscillations approximately corresponding to notes of the tempered scale within a determined range, switching means for changing the effective capacitance value of said capacitive means and thereby to shift said range by at least one octave, a set of individual tuning potentiometers for each range to accurately adjust the frequencies produced, means for selectively energizing said sets of potentiometers in accordance with the range which is operative, and balancing means

for neutralizing the effect of the setting of the set de-energized potentiometers upon the set of energized potentiometers.

7. A solo electrical musical instrument including an electro-acoustic transducer, said instrument comprising in combination a glow-discharge tube having capacitive means connected in series therewith, a conductive path connecting the transducer in the output of said glow-discharge tube, a series of tuned resistances, note-switching means for selectively connecting a selected plurality of said series across said capacitive means and in oscillation-producing relation with said tube thereby to cause said tube to produce oscillations approximately corresponding to notes of the tempered scale within a determined range, range-switching means for changing the effective capacitance value of said capacitive means and thereby to shift said range by at least one octave, a set of individual tuning potentiometers for each range to accurately adjust the frequencies produced, means selectively energizing said sets of potentiometers in accordance with the range which is operative, and balancing resistances interposed between said potentiometers and said switching means for neutralizing the effect of the setting of the de-energized potentiometers upon the energized potentiometers, said tuned resistances being considerably higher in value than said balancing resistances and said balancing resistances being considerably higher in value than said potentiometer.

8. A solo electrical musical instrument employing an electro-acoustic transducer, said instrument comprising in combination a glow-discharge tube, a tuned mesh for said tube, said mesh including a plurality of resistances in parallel, note-switching means for said mesh for connecting any selected resistance in oscillation-producing relation with said tube thereby to cause production of oscillations of step-by-step varying frequencies within a range, means for shifting said range in octave steps, a set of potentiometers for each range to accurately adjust said frequencies, means for rendering said sets selectively operative in accordance with the range, means for neutralizing the effect of the inoperative set of potentiometers upon the energized set of potentiometers, and means effective for all ranges for continuously adjusting the general pitch of the instrument.

9. In an electrical musical instrument including an electro-acoustic transducer and a glow-discharge tube oscillator tunable in steps by means of a tuned mesh including a set of resistances connected in parallel and keying means for connecting any selected resistance in circuit with said tube, a resistance of the order of about 500 megohms to about 2,000 megohms connected across the electrodes of said tube thereby to neutralize the effect of leakage on the constancy of tuning.

NICHOLAS LANGER.
